UNITED STATES PATENT OFFICE.

DENNIS G. FOLEY, OF HARTFORD, CONNECTICUT.

PNEUMATIC TOOL.

SPECIFICATION forming part of Letters Patent No. 730,207, dated June 2, 1903.

Application filed August 29, 1902. Serial No. 121,489. (No model.)

To all whom it may concern:

Be it known that I, DENNIS G. FOLEY, a citizen of the United States, and a resident of Hartford, in the county of Hartford and State 5 of Connecticut, have invented a certain new and useful Improvement in Pneumatic Tools, of which the following is a specification.

The invention relates to pneumatic tools, and more particularly to a tool of this general class adapted to receive and absorb the impact of a blow and at the same time offer sufficient resistance to the blow to effect the required work. From the very nature of the tool and the purpose for which it is designed 15 it might very properly be called a "pneumatic anvil."

The object of the invention is to provide a tool which may be used for various purposes and in various positions, to provide a backing 20 to suitably resist a blow or other mechanical strain incidental to riveting or swaging, or, in fact, for any purpose in the arts.

A further object of the invention is to provide a tool which may be used in more or less 25 inaccessible positions or places and which will have such features of adjustment as to accommodate itself to various conditions of use.

A particular object of the invention is to 30 provide what might be called a "pneumatic anvil" to resist the blow of the hammer or swaging-tool ordinarily employed in the riveting incident to boiler structures or the like.

Referring to the drawings, Figure 1 is a 35 diagrammatic view illustrating the method of using the improved tool. Fig. 2 is a view in side elevation of the device. Fig. 3 is a front view of the improved tool. Fig. 4 is a detail sectional view through the device.

In the accompanying drawings, the numeral 1 denotes the outer plate or shell of a locomotive-boiler, and 2 the inner plate or shell, a water-space being formed between these two plates, this water-space 3 being located adjacent to the fire-box 4. Over the fire-box and within the inner shell are the header-plates 5, into which the fire-tubes 6 are expanded. The water-space 3 is closed at or near its bottom by a mud-ring 7, while 45 a dome-plate 8 is arranged over the tubes 6, an independent plate or shell 9 joining the plates 8 and 2. Stay-bolts 10 are secured to

the inner and outer shells 2 and 1, and in many cases these stay-bolts are located below the meeting or overlapping edges of the 55 plates 9 and 2, this joint being formed in many instances in renewing the lower portion of the inner plate or shell as a whole when it shall have become burned out. These two plates 9 and 2 are ordinarily united by riveting, and it is apparent that in renewing this lower portion of the inner plate or shell the water-space 3 affords a very inaccessible space within which to work or even to place a suitable stop or backing to receive the impact of the blows necessary to upset the rivets 11.

So far as known, in renewing the lower part of the inner shell it has been the practice to insert a wedge or block between the 70 inner and outer shells; but this has many disadvantages from the fact that it is difficult to position the wedge or block without removing the mud-ring, which is undesirable, and even then it is often impossible to position 75 the block or wedge in view of the interference of the stay-bolts, and, further, it is impossible to locate the seam at the desired height from the bottom of the fire-box, for the reason that the wedge or block cannot be inserted 80 in the water-space 3 to the required extent, and a further disadvantage results in using a solid block, which having no resiliency transmits the entire shock of the blow to the outer shell to the detriment of the latter. 85

The improved tool herein described obviates all of these objections and has other advantageous features. Briefly, it consists of an outer or base ring 12, interiorly threaded to receive a casing 13, which provides a pressure-chamber 14, within which is located a piston or anvil 15. This anvil or piston is suitably packed adjacent to the inner wall of the pressure-chamber by a packing-ring 16, which is located in a flange 17, the latter 90 forming an abutment for one end of a spring 18, which normally holds the anvil or piston within the pressure-chamber.

A ring 19 is located within the casing 13 and holds the spring 18 in position. The outer 100 surface of the anvil or piston is preferably slightly concaved in order to center the tool with reference to the rivet to be backed up and held.

It will be noted that the casing 13 and outer or base ring are adjustable, so that the tool may be varied as to thickness, and the outer shell is provided with openings 20, through 5 which a supply-pipe may be inserted and screwed into a socket in the casing 13. This provides a very convenient and delicate though positive adjustment for the parts, the openings 20 being preferably arranged 10 in staggered relation to each other, so that the socket in the casing 13 will register with one of said openings as the casing is moved in or out of the base-ring. By turning the two parts one with reference to the other until 15 one or the other of the openings 20 registers with the socket in the wall of the pressure-chamber and then inserting the supply-pipe the parts will be locked in any desired position of adjustment.

20 The supply-pipe 21 serves also as a handle for placing the tool in position. This pipe is connected with a suitable compressor 22, arranged to give the desired pressure for forcing the anvil 15 outward and against the back 25 of the rivet. For convenience a three-way valve or cock 23 is located in the pressure connections, and by manipulating this air or other fluid under pressure may be admitted to or released from the pressure-chamber 14.

30 In using this tool it is not necessary to remove the mud-ring 7, as the tool when in normal condition is comparatively thin and may be inserted and positioned by simply springing out the lower edge of the plates or casing 35 of the fire-box, as illustrated at 24. After insertion the tool is positioned and the compressed fluid admitted to the pressure-chamber, whereupon the anvil or piston is forced outward until it contacts and presses against 40 the rivet or part to be swaged. The outer or base ring of course bears upon the inner wall of the outer shell, having been made of the approximate thickness to accommodate itself to the space between the two plates before having been inserted. However, owing 45 to the air-cushion between the anvil and base-ring a comparatively small or slight shock is transmitted to said outer shell.

While the improved tool has been de- 50 scribed herein in detail, it is obvious that

many changes may be made in the details of construction and the general organization of the parts without departing from the spirit of the invention, which contemplates providing a resilient or cushioned anvil and, further, one that may be expanded to different degrees. 55

What I claim as my invention, and desire to secure by Letters Patent, is—

1. In combination, a comparatively short 60 base or support having the greater part of its interior surface threaded, a comparatively short casing having the greater portion of its outer surface threaded to fit the thread in the base and having a pressure-chamber, an 65 anvil projecting within the pressure-chamber and a fluid connection for admitting a pressure medium within said chamber.

2. In combination, a base or support, a casing 70 adjustably mounted in the base and having a pressure-chamber, an anvil projecting within the pressure-chamber, a rigid connection for admitting fluid extending from the chamber through the wall of the base and projecting beyond the latter. 75

3. In combination, a base or support having an opening for the entrance of a fluid connection, a casing supported on the base and having a pressure-chamber and an opening to receive the fluid connection, an anvil 80 located within the pressure-chamber, and a fluid connection with the casing.

4. In combination, a base or support having openings staggered with reference to each other, a casing adjustably supported on the 85 base and having an opening adapted to register with the openings in the base, and an anvil projecting into the casing.

5. In combination, a base or support, a casing 90 adjustably supported on the base and having a pressure-chamber, an anvil projecting into the pressure-chamber, a resilient connection between the anvil and casing, and a fluid connection with the pressure-chamber through the base or support.

DENNIS G. FOLEY.
